US00D911476S

(12) **United States Design Patent** (10) **Patent No.:** **US D911,476 S**
(45) **Date of Patent:** **** Feb. 23, 2021**

(54) **POWERED WHEELED BOARD**

(71) Applicant: **RAZOR USA LLC**, Cerritos, CA (US)

(72) Inventor: **Joey Chih-Wei Huang**, Temple City, CA (US)

(73) Assignee: **RAZOR USA LLC**, Cerritos, CA (US)

(**) Term: **15 Years**

(21) Appl. No.: **29/717,684**

(22) Filed: **Dec. 18, 2019**

Related U.S. Application Data

(63) Continuation of application No. 29/664,559, filed on Sep. 26, 2018, now Pat. No. Des. 871,532, which is a continuation of application No. 29/633,000, filed on Jan. 11, 2018, now Pat. No. Des. 829,838, which is a continuation of application No. 29/576,467, filed on Sep. 2, 2016, now abandoned.

(57) **CLAIM**

The ornamental design for a powered wheeled board, as shown and described.

DESCRIPTION

FIG. 1 is a top, rear, left-side perspective view showing a powered wheeled board of my design;
FIG. 2 is a bottom, rear, left-side perspective view thereof;
FIG. 3 is a top view thereof;
FIG. 4 is a bottom view thereof;
FIG. 5 is a left-side view thereof;
FIG. 6 is a right-side view thereof;
FIG. 7 is a front view thereof; and,
FIG. 8 is a rear view thereof.

The broken lines illustrate portions of the powered wheeled board that form no part of the claimed design.

1 Claim, 6 Drawing Sheets
